UNITED STATES PATENT OFFICE.

EDWARD G. BUDD, OF PHILADELPHIA, PENNSYLVANIA, ASSIGNOR TO EDWARD G. BUDD MANUFACTURING COMPANY, A CORPORATION OF PENNSYLVANIA.

DESIGN FOR A VEHICLE-WHEEL FENDER.

51,410.

Specification for Design.

Patented Oct. 23, 1917.

Application filed March 13, 1917. Serial No. 154,622. Term of patent 14 years.

To all whom it may concern:

Be it known that I, EDWARD G. BUDD, a citizen of the United States, residing at Philadelphia, in the county of Philadelphia, State of Pennsylvania, have invented a new, original, and ornamental Design for Vehicle-Wheel Fenders, of which the following is a specification, reference being had to the accompanying drawing, forming part thereof.

Figure 1 is a top plan view of a fender showing my new design.

Fig. 2 is a view in side elevation of the same.

Copies of this patent may be obtained for five cents each, by addressing the "Commissioner of Patents, Washington, D. C."

Fig. 3 is a view in front elevation of the same.

I claim:

The ornamental design for a vehicle wheel fender, as shown.

In testimony whereof I have hereunto set my hand in the presence of the subscribing witnesses, on this third day of March A. D. 1917.

EDWARD G. BUDD.
